UNITED STATES PATENT OFFICE.

SAMUEL R. EARNEST, OF COLORADO SPRINGS, COLORADO.

DESIGN FOR A MEDAL OR SIMILAR ARTICLE.

SPECIFICATION forming part of Design No. 36,211, dated February 3, 1903.

Application filed December 30, 1902. Serial No. 137,210. Term of patent 7 years.

To all whom it may concern:

Be it known that I, SAMUEL R. EARNEST, a citizen of the United States, residing at Colorado Springs, in the county of El Paso and State of Colorado, have invented and produced a new, original, and ornamental Design for a Medal or Similar Article, of which the following is a specification.

My invention relates to a new and ornamental design for a medal or similar article, of which the following is a specification, reference being had to the accompanying drawings, in which—

Figure 1 is the obverse side, and Fig. 2 is the reverse side.

The object of my invention is to produce a medal or similar article to commemorate the event in United States history known as the "Louisiana Purchase." Hence the essen-

tial features of my design are the bust of Napoleon and Jefferson on the obverse side, set in profile, and on the reverse side the representation of an inverted horseshoe, interlaced with a scroll to form a monogram, and adjacent the ends of the horseshoe is the representation of a four-leaf clover.

Having thus described the invention, what I claim as new is—

The ornamental design for a medal or similar article, as shown and described.

In testimony that I claim the foregoing as my own I have hereto affixed my signature in the presence of two witnesses.

SAMUEL R. EARNEST.
